Des. 189,995
Patented Mar. 28, 1961

189,995

BASKET FOR BERRIES OR THE LIKE

Walton B. Crane, South Pasadena, Calif., assignor to Allied Plastics Company, Los Angeles, Calif., a corporation of California

Filed July 18, 1958, Ser. No. 51,835

Term of patent 14 years

(Cl. D58—4)

Fig. 1

Fig. 3

Fig. 1 is a perspective view of a basket for berries showing my new design;

Fig. 2 is a side elevational view thereof; and

Fig. 3 is an end elevational view thereof.

I claim:

The ornamental design for a basket for berries or the like, substantially as shown.
